DESIGN FOR A SERVING TRAY

Livingston S. Hunt, West New Brighton, Staten Island, N. Y., assignor to Roland Hoyt Sloan, West New Brighton, Staten Island, N. Y.

Application November 16, 1933, Serial No. 49,756

Term of patent 3½ years

To all whom it may concern:

Be it known that I, LIVINGSTON S. HUNT, a citizen of the United States, residing at West New Brighton, Staten Island, county of Richmond, and State of New York, United States of America, have invented a new, original, and ornamental Design for a Serving Tray, of which the following is a specification, reference being had to the accompanying drawing, forming a part hereof.

The figure is a perspective view of a serving tray showing my new design.

I claim:

The ornamental design for a serving tray, as shown.

LIVINGSTON S. HUNT.
